MECHANICAL EXCAVATORS

Norman Brocklebank, Beverley, and Roy Wardill and Gordon Scott, Hull, England, assignors to Priestman Brothers Limited, Hull, England, a British company

Filed Aug. 26, 1963, Ser. No. 304,586

Claims priority, application Great Britain, Aug. 23, 1962,
33,006/62

3 Claims. (Cl. 214—138)

It is very desirable for mechanical excavators to be adaptable so that they can be put to as many uses as is reasonably practicable. Commonly, shovels which have a boom and an arm pivoted together with a digging bucket mounted on the outer end of the arm are arranged so that they can be operated both as drag shovels and also face shovels. For this purpose the bucket or shovel should be reversible and may be constructed as described in the copending U.S. patent application of Norman Brocklebank and Gordon Scott, Ser. No. 294,648, filed July 12, 1963.

When the excavator is operating as a face shovel it is desirable for the boom to be shorter than it is necessary for it to be when the excavator is operating as a drag shovel. It is desirable to have the boom shorter when the excavator is operating as a face shovel because the shorter the boom the heavier the load which can be handled by the excavator and also the excavator can clean up excavations better close to itself.

An unduly long boom is of course a disadvantage when an excavator is travelling or is parked.

According to the present invention in an excavator of the kind having a boom and an arm pivoted together with a digging bucket mounted on the outer end of the arm, the boom is in two parts the outer of which is telescopically slidable into the inner and means are provided for fixing the two parts together either in their retracted position with the outer part lying largely within the inner part or in their extended position in which the outer part extends upwards and outwards from the inner part.

With this arrangement the length of the boom can be considerably reduced when the excavator is travelling or is parked. However, the invention is particularly applicable to excavators in which the bucket is reversible on the end of the arm so that the excavator can be used alternatively as a drag shovel or a face shovel. When the excavator is used as a face shovel the boom is retracted, that is to say the outer or upper part is slid telescopically within the lower or inner part of the boom and the resulting boom is extremely rigid and very heavy loads can be handled. The excavator may indeed be one of the kind described in said U.S. application Serial No. 294,648 in which the bucket has two connections one near the top and one near the bottom by either of which the bucket can alternatively be pivotally mounted on the arm and there is a link which is pivoted to the bucket and by which the bucket can be rocked about its pivot on the arm during digging and for discharging its contents, the link incorporating a swivel which allows the bucket, when attached to the arm by one connection, to be disconnected, turned around on the swivel so that the bucket faces in an opposite direction relatively to the arm, and then attached again to the arm by the other connection.

It is desirable for the lower or inner boom part to be the stiffer and for this purpose the lower part may consist of two closed box sections arranged side by side with a bottom plate extending between them. The outer boom part is then arranged to slide on the bottom plate between the two box sections.

Preferably the telescopic arrangement of the two boom

2

parts is combined with the arrangement described in U.S. patent application Ser. No. 304,585, filed August 26, 1963, by Norman Brocklebank and Gordon Scott. Thus the means for fixing the two boom parts together in their extended position allows the outer part to slew from side to side relatively to the inner part and to be fixed to the inner part in any one of three different positions in the first of which the two parts of the boom are aligned with each other so that the axis of the boom is straight as seen from above, and in the other two of which the outer part of the boom is set at angle laterally as seen from above to the inner part of the boom, the outer part being off-set in opposite directions in these two positions.

15 This off-setting of the outer part of the boom to either one side or the other is extremely useful when the excavator is being used as a drag shovel for excavating trenches.

It enables the trench to be excavated alongside a wall or other obstruction by slewing the super-structure of the machine in one sense on the chassis of the machine and slewing the outer upper part of the boom in the other sense relatively to the inner lower part of the boom and locking the two parts together in this relative position. When this is done the vertical plane containing the outer 20 part of the boom is laterally off-set from the central longitudinal line of the chassis so that a trench can be dug which is in line with the side edge of or even outside the wheel base of the chassis.

Preferably the fixing means for fixing the two parts of 30 the boom together in their extended and retracted positions consists of sockets in the two boom parts and a pin which is arranged to pass through aligned sockets in the boom in each position. In order to strengthen the boom, the two parts may additionally be secured together 35 by bolts in the two positions.

One example of an excavator constructed in accordance with the present invention is illustrated in the accompanying drawings, in which:

FIGURE I is a side elevation of the excavator set up 40 for use as a drag shovel with the boom extended;

FIGURE II is a side elevation of the excavator set up for use as a face shovel with the boom retracted;

FIGURE III is a side elevation of the boom per se in 45 its extended position and with the outer part aligned with the inner part;

FIGURE IV is a plan of the extended boom as shown in FIGURE III;

FIGURE V is a side elevation of the boom per se in its retracted position;

FIGURE VI is a plan of the boom as shown in FIGURE V;

FIGURE VII is a section on the line VII to VII in FIGURE IV;

FIGURE VIII is a section on the line VIII to VIII in 55 FIGURE IV; and,

FIGURE IX is a section on the line IX to IX in FIGURE IV.

The excavator, which is the same machine as that illustrated and described in the copending application 60 Ser. No. 304,585, previously referred to, consists of a superstructure 1 which is carried through a turntable 2 on a track laying chassis 3. An inner part 4 of a steel box shaped boom is pivoted at its lower end to a bracket 5 on the superstructure 1. The boom can be raised and lowered by means of a pair of hydraulic rams 6 which extend between lugs 7 on the superstructure and lugs 8 at the outer end of the inner boom part 4.

The upper or outer part of the boom 9, which can telescope within the inner boom part 4, is arranged when 65 extended to slew relatively to the inner part 4 and to be fixed in any one of three different positions relatively to the inner part 4. A digging arm 10 having a plate 11

at each side is pivoted by means of the brackets at 12 to the upper end of the boom part 9 to enable the digging arm 10 to swing backwards and forwards on the other end of the boom. This swinging movement is controlled by a hydraulic ram 13 one end of which is anchored between lugs 14 on the inner end of the outer boom part 9 and the other end of which is anchored to a bracket 15 carried between the plates 11. A digging bucket 16 is pivotally mounted on the outer end of the arm 10 and can be rocked backwards and forwards on the end of the arm by a hydraulic ram 17. One end of the ram 17 is anchored to the plates 11 and the other end is connected to flanges 18 on the back of the bucket through a swivel link 19. The bucket has two alternative connections 20 and 21 by either of which it can be connected to the end of the arm 10. The arrangement is such that the bucket can be disconnected from the arm 10, swung around through 180° on the swivel 19 and reconnected by the other connection 20 or 21 to the arm 10. In this way the excavator can be converted from a drag shovel or back actor to a face shovel and vice versa easily. This arrangement is fully described and claimed in the copending application Ser. No. 294,648, previously referred to.

The construction of the two boom parts 4 and 9 which enables the outer part 9 to slew relatively to the inner part and to telescope into the inner part is shown most clearly in FIGURES II to IX. The inner boom part 4 consists of two box sections 22 arranged side by side and connected by a bottom plate 23 which is welded to them. The two box sections increase in depth from a minimum at the inner end to a maximum a short distance away from the outer end. The inner boom part is therefore substantially U shaped in section and the outer boom part 9 is arranged to slide within the trough of the U between the box sections 22, on the base plate 23, and beneath inturned lips 23a on the inner walls of the box sections. These inner walls of the box sections 22 extend above the sections as they taper in a direction towards the inner end of the boom to provide a channel of constant height to receive the inner end of the outer boom part 9 as it telescopes within the inner part. At their extreme inner ends, the box sections 22 terminate in tubular sockets 24 for receiving a pivot pin which connects the inner end of the boom to the bracket 5. At its extreme outer end, the boom part 4 is strengthened with upper and lower plates 25 and 26 respectively which defines between them an enlarged housing 27 which enables the extreme inner end of the outer part 9 to move from side to side when the outer boom part 9 is slewed relatively to the inner part 4. The bottom plate 26 extends across the full width of the boom but the upper plate 25 has its centre and rear portion cut away to provide access to the housing 27. The lugs 8 for the rams 6 are welded to the top plate 25.

The outer boom part 9 is also of box construction and consists of four plates welded together at each corner of the section. There is a portion 28 of constant height at the inner end of the boom part 9 but beyond this the rest of the boom part tapers towards its outer end. At its extreme outer end the part 9 is formed with a tubular socket 29 for receiving a pivot pin which connects the plate brackets 11 to the end of the boom.

Adjacent its inner end the outer boom part 9 is formed with a tubular socket 30 and adjacent its outer end is formed with another tubular socket 31 of similar shape and size to the first one. The socket 31 is supported by a web 32 where it projects above the tapering box section of the boom part 9 so that it has the same height as the socket 30. When the boom is in its fully extended position as shown in FIGURES I, III and IX, a pivot pin 33 extends down through the socket 30 and through aligned tubular sockets 34 and 35 in the upper plate 5 and in the lower plates 23 and 26 respectively to connect the two boom parts together. The outer boom part 9 is free to slew about the pivot pin 33 but it can be bolted

in any one of three positions in which it extends straight forwards in alignment with the inner boom part 4 as shown in FIGURES III and IV or at an angle of 25° to one side or the other. The outer boom part 9 can be rigidly fixed in the straight ahead position shown in FIGURES III and IV by means of three bolts 36, 37 and 38 which pass through sockets in the inner end of the outer boom part 9 and through holes formed in the bottom plates 23 and 26 of the inner boom part 4. When the outer boom part 9 is slewed to the left or to the right, the bolts 37 and 38 are transferred to holes 39 and 40 or to holes 41 and 39 respectively in the bottom plates 23 and 26 and the bolt 36 is dispensed with. Instead, the inner end of the boom part 9 is bolted to one or other of the side walls of the housing 27 by a pair of bolts which pass through a pair of transverse tubular sockets 42 at the inner extreme inner end of the boom part 9 and through a pair of sockets 43 or 44 in one side wall of the housing 27 or the other. This arrangement is fully described in the copending application Ser. No. 304,585, previously referred to.

The outer boom part 9 can be retracted telescopically within the boom part 4 by unbolting its extreme inner end from the bottom plates or side walls of the housing 27 and removing the pivot pin 33. The outer boom part 9 is then retracted from the position shown in FIGURES I, III and IV to that shown in FIGURES II, V and VI by withdrawing it through the housing 27 until the socket 31 is aligned with the sockets 34 and 35. It is then secured in position by reinserting the pivot pin 33 through the tubular sockets 34 and 35 in the housing 27 and through the socket 31 in the part 9. The inner end of the outer part is also secured by means of the bolts 36, 37 and 38 which now pass through holes 45, 46 and 47 respectively in the plate 23 and in a strengthening plate 48 beneath the plate 23 at the inner end of the boom part 4. The outer boom part 9 cannot of course slew from side to side relatively to the inner part 4 when it is retracted in this way.

The construction of the boom and the mounting of the bucket 16 on the end of the arm 10 enable the excavator to be very adaptable and to be used for a wide variety of functions. If the bucket is mounted as shown in FIGURE I, the machine is ready for use as a back actor or drag shovel. If the two boom parts are extended and locked in the straight ahead position a trench can be dug in line with the central longitudinal line of the chassis. However, if the superstructure 1 is slewed to one side or the other through 25° and the outer boom part 9 is slewed in the opposite sense relatively to the inner boom part 4 through 25° and locked in this position, the excavator can then dig a trench which is in line with one or other of its tracks.

By turning the bucket 16 around on the swivel 19 and reconnecting it to the arm 10 and also retracting the outer boom part 9 within the inner boom part 4, both as shown in FIGURE II, the excavator is ready for use as a face shovel. With the boom retracted in this way, the excavator is also ready for transporting.

We claim:

1. In an excavator of the kind having a body, a boom, means pivotally mounting said boom on said body, a digging arm, means pivotally mounting said digging arm on said boom, a digging bucket mounted on said digging arm; the improvement according to which said boom comprises an inner boom part mounted on said body, an outer boom part carrying said digging arm and adapted to be telescopically slidable into said inner boom part, and means fixing said inner and outer boom parts together either in their contracted position with said outer boom part lying largely within said inner boom part or in their extended position in which said outer boom part extends upwards and outwards from said inner boom part, wherein in said inner boom part comprises parallel, laterally spaced, first and second closed box sections and a bottom

plate extending between said first and second box sections, said box sections and the bottom plate defining a trough dimensioned to slidably receive said outer boom part.

2. In an excavator of the kind having a body, a boom, means pivotally mounting said boom on said body, a digging arm, means pivotally mounting said digging arm on said boom, a digging bucket mounted on said digging arm; the improvement according to which said boom comprises an inner boom part mounted on said body, an outer boom part carrying said digging arm and adapted to be telescopically slidably into said inner boom part, and means fixing said inner and outer boom parts together either in their contracted position with said outer boom part lying largely within said inner boom part or in their extended position in which said outer boom part extends upwards and outwards from said inner boom part, wherein in said fixing means comprises at least one tubular part in a selected one of said boom parts defining a socket therethrough, a plurality of tubular parts spaced lengthwise along and defining a plurality of sockets in the other of said boom parts, one of the sockets in said other boom part being positioned to be in alignment with a socket of said selected boom part when said boom parts are in their contracted position and another of the sockets in said other boom part being positioned to be in alignment with a socket of said selected boom part when said boom parts are in their extended position, and a pin adapted to pass through said aligned sockets.

3. In an excavator of the kind having a body, a boom, means pivotally mounting said boom on said body, a digging arm, means pivotally mounting said digging arm on said boom, a digging bucket mounted on said digging arm; the improvement according to which said boom com-

prises an inner boom part mounted on said body, an outer boom part carrying said digging arm and adapted to be telescopically slidably into said inner boom part, and means fixing said inner and outer boom parts together either in their contracted position with said outer boom part lying largely within said inner boom part or in their extended position in which said outer boom part extends upwards and outwards from said inner boom part, said excavator comprising first connecting means carried by 10 said bucket near the top thereof, second connecting means carried by said bucket near the bottom thereof, third connecting means carried by said bucket intermediate said first and second connections, a supporting link carried from said boom and adapted to support said bucket 15 through said third connecting means, swivel means in said link, and means optionally securing said bucket to said digging arm through one of said first and second connecting means, said bucket being formed to face toward said body for use as a drag shovel when connected to said 20 digging arm through said first connecting means with said boom in its extended position, and to face away from said body for use as a face shovel when connected to said digging arm through said second connecting means with said boom in its contracted position.
